UNITED STATES PATENT OFFICE.

WILLIAM O. GOTTWALS, OF WASHINGTON, DISTRICT OF COLUMBIA.

SHEET-METAL SECTIONAL CABINET.

1,294,087.

Specification of Letters Patent. Patented Feb. 11, 1919.

Application filed October 5, 1917. Serial No. 194,931.

To all whom it may concern:

Be it known that I, WILLIAM O. GOTTWALS, a citizen of the United States, residing at Washington, in the District of Columbia, have invented certain new and useful Improvements in Sheet-Metal Sectional Cabinets, of which the following is a specification.

The invention relates to the manufacture of sheet metal sectional cabinets consisting of counterpart sections adapted to be assembled and detachably secured together in such number and arrangement of sections as is most convenient for the user, and capable of being added to and increased in number as may be required.

In the manufacture of such sections of sheet metal difficulty is experienced in producing the sections of exactly the same dimensions, so that without difficulty they will correspond with each other and fit together as described, and my invention relates to such a cabinet, and to the mode of manufacture of the sections thereof, in which such difficulties are overcome and the sections are, with economy of labor and material, produced of uniformly exact dimensions, the invention also comprising means by which the sections are detachably secured together.

I will describe the invention in connection with an illustration of a cabinet which provides a series of what may be called pigeon-holes, the same being designed to receive drawers to contain papers or index cards, or other devices or materials adapted to be stored in such a cabinet. The cabinet illustrated comprises only four sections, which are sufficient for the illustration of the invention, but it will be understood that the number of sections may extend from unity to any desired and convenient number. The pigeon-holes formed by the sections shown are about six inches wide and four inches high and seventeen inches deep, and are suitable for a standard size of card index drawers, but the dimensions of the pigeon holes may be varied, another larger convenient size being seventeen and one-half inches wide and eleven inches high, which is ap-

proximately a standard size for legal vertical files.

The present invention is not concerned with the construction and supporting means of the drawers, but my invention is well adapted for the application of the usual or improved extension slides and other drawer-guiding and supporting means, with more economy than in the usual constructions of sectional cabinets. The invention is also adapted for the production of library sections without changing the principle of the invention and by merely making the sections of the proper width and depth in proportion to the height.

With such objects in view, as well as other advantages which may be incident to the use of the improvement, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration. In the said drawings:—

Figure 1 is a perspective view of the front portion of a cabinet, consisting of four sections, the same illustrating and embodying my invention.

Fig. 2 is a sectional view of an end portion of a sheet from which the section, or one-half thereof, is formed, the same showing the first bending operation.

Fig. 3 is a similar view showing the second bending operation.

Fig. 4 is a similar view showing the interior stiffening and frame member inserted.

Fig. 5 is a perspective view of one of the sheets after the formation of the box-like end portions, and after the insertion of the

frame and stiffening members, and after the sawing operation.

Fig. 6 is a perspective view of the front portion of such a sheet after the final bending operation.

Fig. 7 is a vertical sectional view on line VII—VII of Fig. 1.

Fig. 8 is a similar view on line VIII—VIII of Fig. 1.

10 Fig. 9 is a perspective view illustrating the elements forming a corner connection between different sections.

Fig. 10 is a sectional view on line X—X of Fig. 8.

15 Fig. 11 is an end view of two angle pieces, for two contiguous sections, united together, when said sections are side by side.

Fig. 12 is a similar view showing the arrangement when said two sections are one 20 over the other.

Fig. 13 is a similar view showing the arrangement when the inner corners of four sections are to be united together.

Fig. 14 is a similar view of a single angle 25 piece, the same representing a finish at a corner of a section which corner is not to be united with another section.

Fig. 15 is a perspective view of a portion of the frame and stiffening member.

30 Fig. 16 is a perspective view of the interior connecting member which fits within the member shown in Fig. 15.

Fig. 17 is a perspective view of a portion of the longitudinal member.

35 Figs. 18, 19 and 20 are perspective views illustrating the method and construction in which the body is formed from a single sheet of metal; also the formation of a retaining groove for the back plate.

40 Figs. 21 to 25 illustrate a modification of the corner securing means for uniting sections together, wherein the angle pieces are attached to the sections and the corner keys are attached to each other.

45 Referring to the drawings, 1 indicates a sheet of metal of sufficient dimension from front to rear, that is to say from the upper to the lower side of Fig. 5 to extend for the depth of the section, and of sufficient dimension, from the right to the left of said figure to constitute one-half of the perimeter of the section. Such sheet of metal will therefore form one-half of one pigeon-hole or section, including one-half of the top, one-half of the vertical sides and one-half of the bottom. The front and rear edges of said sheet are first formed with bends 2 and flanges 3, as indicated at one of the edges of the sheet in Fig. 2, this

50 operation being performed by suitable bending tools or dies. The flange 3 is then formed into a box like form 4 (Fig. 3) by the aid of upper and lower dies 5 and 6 and internal mandrel 7, these instrumentalities

being shown in dotted lines in Fig. 3. I then form of sheet metal two frame stiffening members, a portion of one of such members 8 being shown on a larger scale in Fig. 15, of suitable dimensions, including their flanges, to fit within the box like portions 7 4, and I then drive the members 8 into the said box like portions wherein they extend from end to end of the latter and fit within the same as indicated in Fig. 4.

The said sheet of metal is then placed on the saw table and I cut through the box like portion down to the top surface of the flange 3 with two saw cuts 9 across each portion 4 to produce a structure such as is shown in Fig. 5. This structure is then bent, by suitable bending tools or dies, into the form indicated in Fig. 6, so as to form one-half of a section. Two of such half-sections are then brought together and connecting members 10, formed as shown in Fig. 16, are driven into the horizontal box like portion 4, so as to extend across the meeting vertical plane of the same and securely unite the two half-sections at top and bottom, the said connection, in the case of the top portion of the section being indicated in Fig. 7. It will be understood that each member 10 is of such cross sectional dimension as to fit tightly within the member 8, and of such length as not to extend to the outer ends of the portions 4.

It will be understood that before the half-sections are united, and each is in the condition shown in Fig. 6 it may very conveniently be provided on the inner sides of 10 the vertical wall or in or on the bottom wall, with such attachments or slots as are necessary for the extension slides or other drawer-guiding and supporting instrumentalities, and any slot or cut for such purpose may 10 conveniently be formed when the half-section is in the form shown in Fig. 5.

Longitudinal members 11 (Fig. 17) are employed to permanently unite the two half-sections. These members are formed with 11 flanges 12, one of which flanges fits upon one-half section while the other flange fits upon the other half-section, and said flanges are securely united with the half-sections in any suitable manner, preferably by spot-welding at the points indicated at 13 in Fig. 17. The flanges 12 are slightly bent at 14 to fit over the edges of the flanges 3 (Figs. 7 and 17). It may be here stated that spot-welding, gas soldering or other 12 securing means may be employed between such members as it is found necessary to additionally secure together.

The sections are now ready to have applied thereto the permanent members by the aid of which any section may be secured at any desired corner to a contiguous section. These securing elements referred to may be

termed corner pieces and are of box-like form as indicated at 15 at the middle portion of Fig. 9. The members 15 are formed of sheet metal bent into the form indicated 5 so as to be provided with extensions 16 which may be driven into the members 8 which latter, as will be understood, have previously been combined with the box-like elements 4 of the section. The extensions 10 16 may be driven horizontally into the horizontal members 4 at the tops and bottoms of the sections, as shown in Fig. 8, in which case the outer and lower corner of each member 15 is united with the vertical member 4 by gas welding at the points indicated 15 by 17 in Fig. 8. When so driven into place the extension 16 may abut against or approach the ends of the members 10, as seen in said figure. It will be understood how- 20 ever that the extensions 16 may be driven vertically into the vertical members 4 and the upper inner corners of the members 15 welded to the outer ends of the horizontal members 4.

25 18 indicates the members or angle pieces which are arranged in longitudinal alignment with the members 15 so as to form a part of said securing means. The members 18 are provided with flanges 19 which fit on 30 the corners of the complete section but are not necessarily united thereto. The angle pieces 18 are united together in pairs, as seen in Figs. 11 and 12, which union may be effected by gas welding along the contiguous 35 faces at 19. Where the corners of four sections are to be united the arrangement is or may be such as shown in Fig. 13 where four of the said angle pieces are united together. The angle pieces 18 are used in the assem- 40 bling of the sections together to form a cabinet, and are fitted upon the corners of the sections and are brought into alignment with their respective corner pieces 15, and keys 20 (Fig. 9) inserted, which keys will pass 45 entirely through the members 15 and enter a sufficient distance within the ends of the angle pieces 18. The dimensions of the keys are such that they will have a close fit within the said members but will not be so tight 50 that they cannot be conveniently extracted by means of their heads 21, by which latter they may be pried out so as to vary the arrangement of the sections as may be desired. At any corner of a section where there is no 55 connection with another section, for instance at the four corners of the completed cabinet, single angle pieces 18 (Fig. 14) are or may be used as a finish and will be held in place by keys 20.

60 I may here state that while I have illustrated (referring for example to Figs. 5 and 6) the manufacture of the section in two parts, it may have its four walls and their hollow strengthening bars 4 made from a

single sheet of metal, without any change in 65 principle. In such case the sheet shown in Fig. 5 will be made enough longer to form the entire four walls of the section, Fig. 18 with its front and rear box-like spacing and strengthening bars 4, and two more cuts 9 70 will be made across the latter, one cut for each of the four corners, so that the middle part of the sheet will constitute the top wall of the section, the next contiguous parts will be the vertical side walls, and the end portions of the sheet will each form one half of the bottom, the meeting line of said ends being as shown in Fig. 19.

The provision of the flanges 3, left uncut and continuous around the corners, is 80 important, as they serve to hold down the hollow bars 4 for the entire lengths of their inner edges and confine them regularly and evenly against the walls of the section, whether the section be made of one sheet or 85 of two sheets; for it will be understood that the flanges 3 are stressed and pressed in bending and forming the section.

While I have described the longitudinal connecting members 18 as attached together 90 (Figs. 11 to 13), it will be understood that said members may be omitted and the keys 20 may be attached together in pairs, side by side, Fig. 24 to unite sections that are side by side, or one above the other to unite sections so related, and such union between the sections will be effected by merely inserting such united keys within the box-like corner pieces 15. Or the corner pieces 18 may be employed with their front and rear ends 100 merely extended beyond the flanges 19 Fig. 22 to form or take the place of the said parts 15, and after the said extended ends have been welded in the corners of the sections as already described the sections may be connected together by inserting the said double or quadruple keys Fig. 25 into the said extended ends of the parts 18. The use of the longitudinal members 18 is more important 105 where the sections are of relatively large 110 dimensions, as they serve to space and support the sections along their longitudinal corners.

In order to removably hold the said keys in place, and prevent any relative longitudinal movement of the sections, I may employ springs 22 secured to the corner pieces 15 and having at their free ends pins 23 which enter holes 24 in the keys, Fig. 9.

The described construction of sheet metal 120 cabinet sections is very convenient for the securing within the sections of back pieces 25, Figs. 19 and 20. In forming the sheet, as indicated in Figs. 2 to 5, grooves 26 may be pressed outwardly parallel with and near 125 to the rear ends of the sections, and as the section is brought into its final shape, whether it be made of one sheet or two

sheets, the edges of the back piece 25 of each section are fitted into the grooves 26, and will be securely held after the meeting edges of the section have been secured together.

5. What I claim is:

1. The herein described method of forming sheet metal sections for cabinets, which consists in bending a sheet of metal along its front and rear edges to form hollow bars,

10 cutting across said bars on longitudinal planes, and bending the sheet at right angles on longitudinal lines at said planes and thereby forming the corners of the section, the hollow bars extending on the top, bottom and sides of the front and rear ends of the section.

15 2. The herein described method of forming sheet metal sections for cabinets, which consists in bending a sheet of metal along its front and rear edges to form hollow bars, inserting stiffening members in said bars, cutting across said bars and the stiffening members on longitudinal planes, and bending the sheet at right angles on longitudinal lines at said planes and thereby forming the corners of the section.

20 3. The herein described method of forming sheet metal sections for cabinets, which consists in bending a sheet of metal along its front and rear edges to form hollow bars with base flanges lying on said sheet, cutting across said bars on longitudinal planes and leaving uncut said base flanges, and bending the sheet and said base flanges at right angles on longitudinal lines at said planes and thereby forming the corners of the section.

25 4. The herein described method of forming sheet metal sections for cabinets, which consists in bending a sheet of metal along its front and rear edges to form hollow bars, cutting across said bars on longitudinal planes, and bending the sheet at right angles on longitudinal lines at said planes and thereby forming the corners of the section with angular spaces at the points of said cutting, and then attaching securing members in said angular spaces whereby such sections may be connected together for the building up of a cabinet.

30 5. A cabinet section formed of a sheet of metal bent around at the corners of the section, the front and rear edges of the section being formed with hollow spacing bars, and securing means attached to the section in the angular corner spaces at the ends of said bars.

35 6. In a sectional cabinet, the combination of a plurality of sheet metal sections, the metal of each section being bent at the corners of the section on longitudinal lines, and being bent at the front and rear of the section on horizontal and vertical lines to form horizontal and vertical hollow bars, said sections being fitted together to form a cabinet

net with said hollow bars in mutual engagement. 65

7. In a sectional cabinet, the combination of a plurality of sheet metal sections having their edges folded and thereby forming horizontal and vertical marginal enlargements and angular spaces at the corners, and fitted together with said enlargements in mutual contact, connecting means fitting the corners of the sections, and keys arranged in said corner spaces and engaging said connecting means. 75

8. In a sectional cabinet, the combination of a plurality of sheet metal sections having their edges folded and enlarged and thereby forming horizontal and vertical hollow bars 80 and angular spaces at the corners, hollow corner pieces secured in said corner spaces and secured each to its own section, hollow connecting corner bars secured to each other and arranged along the corners of the sections in line with said corner pieces, and keys engaging said corner pieces and said corner bars and uniting said sections to form a cabinet. 85

9. In a sectional cabinet, the combination 90 of a plurality of sheet metal sections, the metal of each section being bent at the corners of the section on longitudinal lines, and being bent at the front and rear of the section on horizontal and vertical lines to form 95 horizontal and vertical hollow bars and stiffening members inserted in said hollow bars, said sections being fitted together to form a cabinet with said hollow bars in mutual engagement. 100

10. In a sectional cabinet, the combination of a plurality of sheet metal sections, the metal of each section being bent at the corners of the section on longitudinal lines with ends of the metal abutting to form a joint, 105 and being bent at the front and rear of the section on horizontal and vertical lines to form horizontal and vertical hollow bars, and connecting members inserted in said hollow bars and extending across the said 110 joint, said sections being fitted together to form a cabinet with said hollow bars in mutual engagement.

11. The herein described sheet metal section for cabinets, which consists in a sheet 115 of metal bent along its front and rear edges to form hollow bars and cut across on longitudinal planes, and bent at right angles on longitudinal lines at said planes thereby forming horizontal and vertical enlargements at the top, bottom and sides of the front and rear ends of the section, and the longitudinal corner recesses of the section. 120

12. A cabinet section formed of a sheet of metal bent around at the corners of the section, the front and rear edges of the section being formed with hollow spacing bars and inwardly extending flanges 3, the hollow

bars being cut across and said flanges being continuous and bent at the corners, and securing means attached to the section in the angular corner spaces at the ends of said 5 bars.

13. In a sectional cabinet, the combination of a plurality of separate sections, hollow angle pieces arranged at the corners of the sections and having flanges embracing said 10 corners, the contiguous angle pieces being

united to each other, and means for detachably connecting the angle pieces each to the section which it embraces.

In testimony whereof I affix my signature in the presence of two witnesses.

WILLIAM O. GOTTWALS.
